[57] CLAIM

The ornamental design for a liquid dispenser, as shown and described.

DESCRIPTION

FIG. 1 is a perspective view of the liquid dispenser of the present invention;

FIG. 2 is a top plan view of the liquid dispenser;

FIG. 3 is a side elevational view of the liquid dispenser of the invention, the opposite side elevational view being a mirror image thereof;

FIG. 4 is a front elevational view of the liquid dispenser of FIGS. 1-3;

FIG. 5 is a rear elevational view of the liquid dispenser of FIGS. 1-4;

FIG. 6 is a perspective view of a liquid dispenser in accordance with a second embodiment of the invention;

FIG. 7 is a top plan view of the liquid dispenser illustrated in FIG. 6;

FIG. 8 is a side elevational view of the liquid dispenser of FIGS. 6-7, the opposite side elevational view being a mirror image thereof;

FIG. 9 is a front elevational view of the liquid dispenser illustrated in FIGS. 6-8;

FIG. 10 is a rear elevational view of the liquid dispenser illustrated in FIGS. 6-9;

FIG. 11 is a perspective view of a liquid dispenser in accordance with a third embodiment of the invention;

FIG. 12 is a top plan view of the liquid dispenser illustrated in FIG. 11;

FIG. 13 is a side elevational view of the liquid dispenser illustrated in FIGS. 11-12, the opposite side elevational view being a mirror image thereof;

FIG. 14 is a front elevational view of the liquid dispenser illustrated in FIGS. 11-13;

FIG. 15 is a rear elevational view of the liquid dispenser illustrated in FIGS. 11-14;

FIG. 16 is a perspective view of a liquid dispenser in accordance with a fourth embodiment of the invention;

FIG. 17 is a top plan view of the liquid dispenser in FIG. 16; FIG. 18 is a side elevational view of the liquid dispenser illustrated in FIGS. 16 and 17, the opposite side being a mirror image thereof;

FIG. 19 is a front elevational view of the liquid dispenser illustrated in FIGS. 16-18; and,

FIG. 20 is a rear elevational view of the liquid dispenser illustrated in FIGS. 16-19.
